UNITED STATES PATENT OFFICE.

WILLIAM GANLEY, OF PITTSBURGH, PENNSYLVANIA, ASSIGNOR TO RADIUM DIAL COMPANY, OF PITTSBURGH, PENNSYLVANIA.

INDICATING AND IDENTIFYING MEANS.

1,377,065.

Specification of Letters Patent.

Patented May 3, 1921.

Application filed March 20, 1918. Serial No. 223,508.

To all whom it may concern:

Be it known that I, WILLIAM GANLEY, a citizen of the United States, and a resident of Pittsburgh, in the county of Allegheny and State of Pennsylvania, have invented 5 certain new and useful Improvements in Indicating and Identifying Means; and I do hereby declare the following to be a full, clear, and exact description of the invention, 10 such as will enable others skilled in the art to which it appertains to make and use the same.

This invention relates to indicating and identifying means, and particularly to such 15 as are adaptable for use on vehicles.

It frequently happens in war zones that trains of army motor trucks are required to travel at night in close order and without lights over roads comparatively close to 20 the enemy's lines, and when the night is very dark considerable danger is encountered in preventing collisions and other mishaps, and furthermore, the identity of the trucks cannot readily be determined in the 25 dark. Similar conditions may arise with other army vehicles traveling singly or in groups, and also with boats.

The object of my invention is to provide 30 means whereby the difficulties and danger heretofore encountered under the conditions above outlined may be overcome and yet afford an indicator on the vehicle which can be seen from a limited distance to denote the presence and location of the 35 vehicles and also denote the identity of the branch of the service to which they may belong.

With this and other objects in view, the 40 invention consists in certain novel features of construction and combinations of parts as hereinafter set forth and pointed out in the claim.

In the accompanying drawings, Figure 1 45 is a sectional view illustrating my improvements, and Fig. 2 is a face view.

1 represents a frame or back plate which 50 may be made of sheet steel pressed into shape and said plate is provided with lugs 2 somewhat offset from the plane of the back and adapted to rest against a part of the vehicle to which the device is to be secured. The plate 1 is so formed as to provide a depression 3 surrounded by an annular seat 4 for the peripheral portion of a 55 disk 5 of celluloid or other transparent or

partially transparent material. This disk is provided on its face, preferably its rear face, with a coating 6 of mildly luminous material consisting of radio-sensitive material, such as zinc sulfid having combined therewith a radio-active material such as a salt of radium in such quantity as will render the radio-sensitive material mildly but permanently luminous in the dark. The shallow chamber formed by the depression 3 of the back plate will serve to prevent contact of the coated rear face of the disk with the front face of the plate 1, and thus said coating will be protected.

The coated disk 5 is retained on its seat 70 by means of a gasket 7 of fiber, rubber or other suitable material, and said gasket is recessed to receive the edge portion of the disk and prevent lateral displacement of the same.

An identification plate or frame 8 is disposed in front of the coated disk and is provided with lugs to overlie the lugs 2 of the back or frame plate. This plate or frame 8 may be made of comparatively thin sheet metal and has an opening 10 therein, the configuration of which may conform to the shape of an emblem of a branch of the military service or other identifying symbol. In the drawing, I have shown the 85 identifying emblem or symbol in the form of a cross, but it will be understood that the emblem may represent a star or other known insignia or even one or more figures or letters.

The identification plate or frame may be formed to receive a plain glass plate 11 disposed between said plate or frame 8 and gasket 7 to protect the luminous disk from 90 injury and dirt.

The lugs 2 of the back plate 1 and the lugs 9 of the identification plate or frame 8 are perforated for the passage of bolts 12, each of which may be provided with a head 13 at one end threaded to receive nuts 14, 100 whereby the several parts are held together, and if desired, washers 15 may be disposed between the heads of said bolts and the lugs 9. The bolts 12 also serve as means for securing the device to a motor truck or other 105 vehicle.

With the use of my improvement so positioned on a motor truck or other vehicle that may be seen for a short distance from the rear, danger of one motor truck of a 110

- train colliding with another will be avoided, but the luminosity afforded by the coated disk will be so mild that it cannot be seen for a sufficient distance to give information 5 to the enemy, and by the employment of the identification plate or frame which will give to the luminous area the configuration of an emblem or symbol, the identity of the vehicle may be readily determined.
- 10 Slight changes might be made in the details of construction of my invention without departing from the spirit thereof or limiting its scope and hence I do not wish to restrict myself to the precise details here- 15 in set forth.
- Having fully described my invention what I claim as new and desire to secure by Letters-Patent, is:—
- 20 The combination with a frame plate, of a disk of transparent material disposed over said frame plate and having its major portion spaced from said frame plate, said disk

having its rear face coated with luminous material and spaced from the frame plate whereby said coating will be protected, a 25 recessed gasket disposed on said frame plate and overlying the edge portion of the coated disk, a front plate having an opening forming a character designation and provided with a part overlying said gasket, a transparent plate disposed between said gasket and said front plate, and means whereby the frame plate and front plate are secured together with the transparent coated disk, gasket and transparent plate clamped be- 30 tween them. 35

In testimony whereof, I have signed this specification in the presence of two subscribing witnesses.

WILLIAM GANLEY.
